UNITED STATES PATENT OFFICE.

SAMUEL F. CARPENTER, OF PAWTUCKET, RHODE ISLAND.

SELF-CENTERING SPINDLE.

SPECIFICATION forming part of Letters Patent No. 740,354, dated September 29, 1903.

Application filed February 7, 1903. Serial No. 142,390. (No model.)

To all whom it may concern:

Be it known that I, SAMUEL F. CARPENTER, a citizen of the United States, residing at the city of Pawtucket, in the county of Providence and State of Rhode Island, have invented certain new and useful Improvements in Self-Centering Spindles, of which the following is a specification.

My invention consists, first, in a bolster mounted upon a collar in the upper part of the bolster-case; second, in a tapering step whose smaller end rests upon the bottom of the bolster-case and its larger end in contact with the circular bore of the same, and, third, in a locking device for the bolster and a locking device for the step whereby each is restrained from rotation, while otherwise there is liberty of movement necessary for the perfect operation of the spindle.

Referring to the drawings, Figure 1 is a view, partly in section and partly in elevation, of a spindle as embodying my improvements. Fig. 2 is an elevation view of the bolster which forms a part of my improvements. Fig. 3 is an elevation view of the step-support for the spindle. Fig. 4 is a cross-section as seen in line X X of Fig. 1.

Like letters indicate like parts.

A is a bolster-case interiorly of a larger diameter from the shoulder *f* upward. The bolster-case A is provided with locking-pins *a* and *a'*, whose purpose is obvious.

B is a step-support for the spindle C, whose pintle occupies a socket in the top of the step B. The step B is in the shape of a frustum of a cone whose smaller end rests upon the bottom of the bolster-case and whose lateral contact with the wall of the bolster-case is at the perimeter of its upper end. The cavity in the upper part of the step B has a larger diameter than the pintle *c* of the spindle, or preferably the cavity may be made tapering, as shown in Fig. 1. In either instance the step B will have freedom to move when acted upon by the spindle.

In the operation of the spindle C the step B is acted upon as a lever of the third class, the power being at *c*, the fulcrum at *d*, and the resistance at *b*, on which account the ac-

tion of the spindle C upon the step B being 50 at mechanical disadvantage insures against extreme sensitiveness of the spindle to varying conditions attending its operation, while it has sufficient freedom of foot movement for any adjustment necessary to its perfect operation.

D is a bolster mounted within the bolster-case A upon a collar *e*, which rests upon the shoulder *f* of the bolster-case interior. A cross-sectional view of the collar *e* is shown in Fig. 4, *e'* being a slot in the same to permit the collar to pass the locking-pin *a* when being placed in the bolster-case upon the shoulder *f*. The collar *e* has an interior diameter sufficient for the spindle to pass through without contact therewith. The bolster D is adapted to tip when acted upon by the spindle C, its lower end having liberty of lateral movement upon the collar *e*. For this purpose the bolster has a convex annular enlargement near its upper end which is in contact with the bore of the bolster-case, and the portion of the bolster which is below said enlargement is of a diameter less than the diameter of the bore of the bolster-case, so that the bolster is 70 capable of an oscillating movement. The bolster D and the step B are mechanically distinct and independent in their operation, while both contribute, each in its way, to the perfect operation of the spindle. The bolster 80 D and the step B are provided with my improved locking device.

In locking devices heretofore in use the locking-pin has engaged the bolster or the step in a narrow and shallow channel, which 85 device, while it restrains from rotation, is liable otherwise to injuriously restrict the movement of the bolster or of the step.

In my device the locking-channel *g* or *g'* terminates in a circular cavity or ward *h* or *h'*, deeper and of a diameter greater than the width of said channel. In my invention the locking-slot of previous devices is made into an entering channel or guide which leads to the locking-ward *h* or *h'*, in which the locking-pin *a* or *a'* can have contact with the bolster A or the step B at the place only where it restrains from rotation. Consequently it

can restrict the movement of the bolster or of the step in no other way.

In the large upper end of the step B is a conical socket to serve as the seat of the conical pintle of the spindle, but of a diameter exceeding the diameter of said pintle, thus enabling the spindle to gyrate in said seat.

The collar e may be dispensed with without in any manner changing the mechanical principle involved in my invention, and if it is omitted the lower end of the bolster will then rest upon the shoulder f directly and be laterally movable thereon.

Having described my improvements, what I claim, and desire to secure by Letters Patent, is—

1. In a spindle-support, the combination with a spindle, a bolster-case, a bolster and means for restraining the same from rotation; 20 of a frustum-of-a-cone-shaped step resting upon the bottom of the bolster-case, the top of said step at its periphery adapted to engage the interior wall of the bolster-case and constituting a fulcrum upon which the step 25 is moved laterally at its lower end to enable the spindle to overcome the tendency to gyration under an unbalanced load, substantially as set forth.

2. In a spindle-support, the combination of 30 a spindle having a conical pintle, a bolster-case having a circular transverse shoulder in the bore thereof, a collar loosely surrounding the spindle and resting on said shoulder, a tubular bolster having an enlarged portion 35 adapted to contact with the bore of the bolster-case and its lower end resting on said collar, means to restrain said bolster from rotation, a step in the shape of a frustum of a cone having its larger upper end in contact with 40 the bore of the bolster-case and provided with a conical socket in its said upper end of a diameter exceeding the diameter of the pintle of said spindle, and means to restrain said step from rotation while not otherwise restricting its motion, substantially as set forth.

3. In a spindle-support, in combination with a spindle, a bolster-case, a bolster, a step and a locking-pin; of a locking-ward consisting of a longitudinal channel in said bolster, terminating in an enlarged cavity adapted to receive said locking-pin and to restrain said bolster from rotation, while not otherwise restricting its motion, substantially as set forth.

4. In a spindle-support, in combination with a spindle, a bolster-case, a bolster, a step and a locking-pin; of a locking-ward consisting of a longitudinal channel in said step terminating in an enlarged cavity adapted to receive said locking-pin and to restrain the step from rotation, while not otherwise restricting its motion, substantially as set forth.

5. In a spindle-support, the combination of

a spindle, a bolster-case, a tubular bolster having an enlarged portion adapted to contact with the bore of the bolster-case but having the portion below the enlargement of a diameter less than that of the bore of the bolster-case and provided with a longitudinal channel on one side thereof terminating in a round opening of a diameter exceeding the width of said channel, and a locking-pin extending through the side of the bolster-case and adapted to enter said channel and engage with said opening of the bolster, substantially as specified.

6. In a spindle-support, the combination of a spindle, a bolster-case, a bolster, a step in the shape of the frustum of a cone having a plane lower end and supported by and movable laterally on the straight bottom of the bore of the bolster-case and its upper end in contact with said bore and provided with a longitudinal channel on one side thereof terminating in a round opening of a diameter exceeding the width of said channel, and a locking-pin extending through the side of the bolster-case and adapted to enter said channel and to engage with said opening of the step, substantially as specified.

7. In a spindle-support, the combination of a spindle having a conical pintle, a bolster-case, a bolster, a step in the shape of the frustum of a cone having its larger upper end in contact with the bore of the bolster-case and provided with a conical socket in its said upper end of a diameter exceeding the diameter of said pintle, and means for locking said step from rotation without preventing its motion otherwise, substantially as described.

8. In a spindle-support, the combination of a spindle having a pintle, a bolster-case, a tubular bolster having an enlarged portion adapted to contact with the bore of the bolster-case but having the portion below the enlargement of a diameter less than that of the bore of the bolster-case and provided with a longitudinal channel on one side thereof terminating in a round opening of a diameter exceeding the width of said channel, a locking-pin extending through the side of the bolster-case and adapted to engage with said opening of the bolster, a step in the shape of the frustum of a cone having a plane lower end and supported by and movable laterally on the straight bottom of the bore of the bolster-case and its upper end in contact with said bore and provided with a longitudinal channel on one side thereof terminating in a round opening of a diameter exceeding the width of said channel, and a locking-pin extending through the side of the bolster-case and adapted to enter said channel and to engage with said opening of the step, substantially as specified.

9. In a spindle-support, the combination of a spindle, a bolster-case, a bolster having an enlargement at or near the top thereof which is in contact with the bore of the bolster-case but whose lower portion has a diameter less than that of said bore, a step adapted to support said spindle and having its upper end in contact with said bore but its lower portion

of a diameter less than that of said bore, substantially as described. ¹⁰

In testimony whereof I affix my signature in presence of two witnesses.
